SUBSCRIBER CARRIER CHANNEL UNIT COVER OR SIMILAR ARTICLE

Gene L. Stumpf, Belmont, and James R. Stewart, San
Jose, Calif., assignors to GTE Automatic Electric
Laboratories Incorporated, Northlake, Ill.

Filed June 5, 1972, Ser. No. 260,065

Term of patent 14 years

Int. Cl. D14—03

U.S. Cl. D26—14 A

FIG. 1 is a front perspective view of a subscriber-carrier channel unit cover or similar article embodying our new design;

FIG. 2 is a front perspective view taken from the bottom and the left side thereof with the printed circuit card removed;

FIG. 3 is a front elevation view thereof;

FIG. 4 is an elevation view of the right side thereof;

FIG. 5 is a rear elevation view for FIG. 2; and

FIG. 6 is a section view taken along line 6—6 in FIG. 1, with a major portion of the cover broken away.

The broken lines representing the printed circuit card are shown for illustrative purposes only.

We claim:

The ornamental design for a subscriber carrier channel unit cover or similar article, as shown and described.
